UNITED STATES PATENT OFFICE.

DAVID M. SMYTH, OF PASADENA, CALIFORNIA.

ORE-STAMP.

SPECIFICATION forming part of Letters Patent No. 605,615, dated June 14, 1898.

Application filed June 9, 1897. Serial No. 639,935. (No model.)

To all whom it may concern:

Be it known that I, DAVID M. SMYTH, a citizen of the United States, residing at Pasadena, in the county of Los Angeles and State of California, have invented an Improvement in Ore-
5 Stamps, of which the following is a specification.

In mining machinery vertical-acting stamps
10 have been made use of for pulverizing auriferous materials both dry and in connection
with a supply of water. There is, however,
considerable friction in the mechanism that
gives motion to the stamps, and the blow of
the stamp is often sluggish and not well adapted
15 to finely pulverize the ore. I am aware
that drilling and other tools have been actuated
by the reciprocating cores of electric solenoids;
but these have not been well adapted
20 to use in a stamp-mill where there are several
stamps in operation at the same time.

In the present improvements the stamps
are actuated by electromagnetism, and two
stamps are so connected that one stamp is
25 raised as the other one is projected downward,
thereby causing the stamps to work in unison and lessening the electromotive
force necessarily provided in actuating such
stamps.

The drawing is a diagrammatic elevation
30 illustrative of two stamps, their actuating-
helices, and switch and circuit connections to
a battery or other source of electric energy.

The stamps A B are of any desired character, and the material to be pulverized is introduced upon a bed D, either dry or in connection with water, in any desired manner, and the stamps advantageously are operated vertically, and a suitable frame C, with cross-bars E, is provided for supporting the helices
35

F G H I, through which the stamps A B are free to reciprocate, and to the binding-posts K L conductors are led from a battery or other source of electric energy, and there is a switch N, having arms 2 and 3, acted upon by the stamps and serving to move the switch to the contact 5 and then to the contact 4, and the circuit connections are arranged substantially as indicated—that is to say, the return-wires 9 6 7 8 from the respective helices lead
40 to the binding-post K and the negative electrode, and the wire 10 leads from the positive electrode to the switch N, and the contact 5

of the switch is connected by the wire 11 to the magnet H and by the wire 12 to the magnet F, and the contact 4 is connected by the wire 13 to the magnet I and by the wire 14 to the magnet G.

When a current is supplied to the apparatus and the parts are in the position shown in the diagram, the current passes from 10 through N 5 11 to H and by 9 to K, and the helix H draws up the stamp B, and in so doing the upper end of the stamp turns the switch N, so that it is separated from the contact 5 and engages the contact 4. While the switch N remained on the contact 5 the circuit also was closed through the wire 12 to the helix F and by the wire 7 to the binding-post K. Hence as the stamp B is raised the stamp A is forcibly drawn down by the action 70 of the electromagnet F, the magnet G at this time being out of circuit. Thereby a forcible blow is struck upon the materials intervening between the stamp A and the bed D.

As the switch N is changed from 5 to 4 by 75 the upward movement of the stamp B the circuit connections are reversed and the magnet G energized through 4, 14, and 6, so as to lift the stamp A, the magnet F being out of circuit, and at the same time the magnet I is 80 energized through 4, 13, and 8, so as to pull down the stamp B with considerable rapidity and force for pulverizing the materials between such stamp B and the bed D. By this arrangement the two stamps are made to work 85 in unison and the upward movement of one changes the circuit connections to itself and to the other, so that one stamp is drawn up while the other one is accelerated in its downward movement by the action of the magnetism.

It will be apparent that one switch may be made to work with any desired number of stamps, the circuit connections being simply duplicated, and one set of stamps will be elevated simultaneously while the other set of stamps falls, and their movements are accelerated by the magnetic action.

It is advantageous to arrange the parts in such a manner that the rod of the stamp will project above the top of the upper helix less than the lower end of such rod is below such helix in order that the electromagnet may have sufficient force for raising the stamp and
100

that the movement may be always sufficient to turn the switch.

I claim as my invention—

1. The combination with the stamps and the electromagnets for actuating the same, of a switch that is actuated by an upward movement of one stamp to change the circuit connections for raising another stamp, substantially as specified.
- 10 2. The combination with two stamps and the electromagnets for actuating the same,

of circuit connections and a switch that is changed by the upward movements of the stamps alternately, for energizing the magnets and raising one stamp and accelerating the fall of the other, substantially as specified.

Signed by me this 1st day of June, 1897.

DAVID M. SMYTH.
